UNITED STATES PATENT OFFICE.

HUBERT ELWELL SMITH, OF LONDON, ENGLAND.

OPERATING DEVICE FOR MOTOR-DRIVEN PUMPS.

Application filed May 17, 1923. Serial No. 639,687.

To all whom it may concern:

Be it known that I, HUBERT ELWELL SMITH, a subject of the King of Great Britain and Ireland, residing at 6 London

5 Street, London, W. 2, England, have invented new and useful Improvements in an Operating Device for Motor-Driven Pumps (for which I have filed application in England on the 30th May, 1922, patent applica-
10 tion No. 15,185/1922), of which the following is a specification.

This invention relates to gasoline lighting plants, that is to say to apparatus in which a small percentage of gasoline or 15 other suitable hydrocarbon is admixed with air for the purpose of lighting and heating in small towns, villages, country houses, factories and the like. Such apparatus includes an air-pump, a device for supplying 20 and vapourizing gasoline and a floating holder for air or mixture, and is commonly driven by a water motor. The head of water available for the purpose differs greatly in different places; and it has hitherto been 25 necessary for manufacturers to provide several different types of motor for a given size of gasoline plant, in order approximately to suit all the circumstances that are encountered in practice.

30 The object of this invention is a standardized gasoline lighting plant which may readily be adapted to varying circumstances without replacement of the driving motor.

More specifically the invention is a combination of a water-motor and air-pump in 35 a gasoline lighting plant, with a lever rocked by the motor and driving the air-pump, and means for varying the ratio of the lever arms at which the pump and motor are re-
40 spectively set.

A preferred embodiment of the invention comprises a reciprocating water-motor and a reciprocating air-pump set with their axes parallel, and connected together by a lever 45 which fulcrums on a link pivoted to a frame member extending at right angles to the axes of the pump and motor and in their plane. One of the three points of connection to the lever, that is to say, the fulcrum 50 where the link is connected, or the point of connection of the motor, or the point of connection of the pump, is made adjustable

along the lever. Most conveniently the link is thus adjusted, pairs of corresponding holes being made in the lever and the frame 55 member for its accommodation.

In the accompanying drawings,

Figure 1 shows so much of a gasoline lighting plant as is necessary to explain the invention, and

Figure 2 illustrates a modification.

In Figure 1 *a* is a pumping bell joined by a rod *b* to a lever *c* which is pivoted at its distant end upon a link *d*. The cylinder of the water motor is indicated at *e*. Its piston 65 rod *f* is guided by means of a bracket *g* to move in a straight line, and has a pin and slot connection with the lever *c*.

For the purpose of the invention the link *d* is pivoted on a frame member *h*, and provision is made for adjusting it along this member and along the lever *c*. The adjustment may if desired be continuous, but it is sufficient to provide as shown a number of holes *k* in the lever with corresponding 70 holes *l* in the frame member to receive the pins by which the link *d* is joined to the lever and frame member respectively. By shifting the link from one position to another the ratio of the lever arms at which 75 the water motor and the pumping bell respectively operate can be varied. Links of different lengths may be provided for different settings if desired.

In the construction of Figure 2 the frame 85 member *m* has openings *n* in it of sufficient size to receive the cylinder *o* of the water motor, which can be secured in any one of the holes by bolting its flange *p* to the frame member. The piston rod *q* of the water motor 90 can correspondingly be connected with the lever *r* at any one of the holes *s* corresponding with the openings *n*. As before the lever is pivoted upon a link *t* and is connected at its end with the piston rod *u* of the 95 pumping bell.

If the openings *n* are lengthened until they coalesce the adjustment may be made continuous, but for practical purpose it is sufficient to provide a plurality of openings covering the desired range of leverage.

As the size of the floating holder controls the output of the machine, further standardization can be made by using one size of

motor and pumping bell for a range of many models varying simply the size of the floating holder and other standard equipment for other parts of the apparatus.

5. What I claim is:

1. In a gasoline lighting plant the combination of a reciprocating air-pump, a reciprocating water-motor parallel with said air-pump, a frame supporting said pump and motor, a frame member extending at right angles to the axis of said pump and motor and in their plane, a link pivoted on said frame member, a lever connected to said link and to the moving parts of said motor and pump, and means for varying the relative lengths of said lever from the

link to the motor and to the pump respectively.

2. In a gasoline lighting plant the combination of a reciprocating water-motor, a reciprocating air-pump, a lever pivotally connected to the moving parts of said motor and pump and having a plurality of perforations therein, a frame member beneath said lever and having corresponding perforations, and a link adapted to be connected with said lever and said frame member at any pair of corresponding perforations.

In testimony whereof I have signed my name to this specification.

HUBERT ELWELL SMITH.
